UNITED STATES PATENT OFFICE.

OWEN L. SEWARD, OF MERIDEN, CONNECTICUT.

COUNTING MECHANISM.

Application filed August 27, 1925. Serial No. 52,774.

This invention relates more particularly to the transfer movements or carry-up mechanisms of counting devices, and it is especially adapted for commercial counters which are provided for enumerating the actions of rapidly operated machines.

The object of the invention is to so design and arrange the transfer elements that the device may be constructed with a minimum number of parts which co-act smoothly and thereby can be produced at a low cost and can be run for an indefinite period at high speeds without breaking down or getting out of repair.

In mechanisms of this class as one numeral wheel is given a complete revolution the numeral wheel of the next higher denomination is turned one step. In prior structures in order that the number on the higher wheel remains exposed before a window in the casing for substantially all of the revolution of the lower wheel and turn during a short part of the movement of the lower wheel, ratchet and pawl mechanisms, worm wheels and worms, and a plurality of intermediate gears, have been employed for effecting the transfer movements from the lower to the higher numeral wheels. The object of the present invention is attained by the use of directly engaged eccentric or elliptical gears driving a crank and star wheel for transmitting the movements from the lower to the higher wheels, and thereby in a smooth, easy and durable manner, with a gradual yet rapid action, obtain quick transfer movements without the interposition of the prior more complicated mechanisms.

The invention is applicable to both dial counters, that is, those in which the numerals are placed on the faces of disks, and to cylinder counters, that is those in which the numerals are located on the peripheries of wheels.

In the accompanying drawings Fig. 1 is a face view of a dial counter showing the numeral disks as in the act of moving. Fig. 2 is a central longitudinal section of the same. Fig. 3 is a partial section on the plane indicated by the dotted line 3-3 on Fig. 2, the transfer elements being shown in mid

position as when turning all of the disks. Fig. 4 is a face view of a single transfer unit with the elements related as after the higher disk has been turned. Fig. 5 is a transverse section of a cylinder counter on the plane indicated by the dotted line 5-5 on Fig. 6, the elements being shown in mid position. Fig. 6 is a front elevation of the cylinder counter with the casing and portions of the other elements in section.

In the form of dial counter illustrated there is a frame consisting of a front plate 1, a back plate 2, and side walls 4. On the front of the frame is a face plate 6 with windows 7, 8 and 9 through which the numbers on the disks are exposed. The first or lowest numbered disk 10 is attached to a spindle 11 rotarily supported by the frame plates. This spindle is extended through the back plate and is designed to be continuously rotated from any suitable part of the machine, the actions of which it is desired to count. Attached to this spindle is an eccentric gear 12 that is engaged with an eccentric gear 13 fastened to the short spindle 14 which is rotarily supported by the front frame plate and by an intermediate plate 15. The eccentricities of these gears in the form shown are as three to one, and they are so engaged that the longer radius of one meshes with the shorter radius of the other. Fastened to the eccentric gear 13 is a disk 16 and projecting forwardly from this disk is a crank pin 17. This pin is designed to enter the notches 18 in a star wheel 19 which is fastened to the spindle 20, rotarily mounted in the frame plates. Fastened to the front end of the spindle 20 is the second or next higher numeral disk 21 and to the back end an eccentric gear 22.

The eccentric gear 22 meshes with an eccentric gear 23 fastened on the short spindle 24 that is rotarily supported by the back frame plate and an intermediate plate 25. Attached to the gear 23 is a disk 26 that has a forwardly extending crank pin 27 designed to enter the notches 28 of the star wheel 29 that is fastened to the spindle 30 which is rotarily supported by the frame plates and has attached to its front end the next higher numeral disk 31.

When this device is applied to a machine and the driving spindle 11 is rotated the digits on the lowest disk are exposed in succession through the first window 7. As the 5 driving spindle and lowest disk about complete one rotation the eccentric gears 12 and 13 carry the crank pin 17 into a slot of the star wheel 19 and turn it and the second numeral disk 21 one step, causing a figure 10 to be exposed through the window 8. At the tenth turn of the star wheel and disk 21 the eccentric gears 22 and 23 through the crank pin 27 and star wheel 29 give the numeral disk 31 one turn, that is, after each nine 15 rotatory movements and during the tenth movement of a lower disk the next higher disk is turned one step. But three numeral disks and two transfer mechanisms are illustrated. These, however, may be multiplied 20 by the addition of other disks and transfer mechanisms as many times as desired in order that the counter may show as high a reading as is required.

The elliptical gears are so related that 25 when the short radius of a driving gear is engaged with the long radius of a driven gear, the speed of the driven gear to the speed of the driving gear is as one to three, and when the long radius of the driving gear is engaged with the short radius of the driven gear the speed of the driven gear to the speed of the driving gear is as three to one, or in other words, the speed of the driven gear varies as from one to nine, 30 consequently when the crank pin rotated by the driven gear enters the slot of a star wheel, the star wheel is turned one step very rapidly. Furthermore the crank pin carried by the gear that is driven enters the 35 slot of the star wheel tangentially and without violent impact and as it is close to the axis of the driven gear this tends to increase the speed of the star wheel. In the design illustrated each star wheel is moved one 40 step in about one-tenth of a revolution of the lower driving gear, with a smooth and 45 easy, yet quick movement.

In the cylindrical type of counter illustrated there is a circular casing 32 with a 50 removable head 33 at one side and a window 34 in the periphery. The driving spindle 35 is rotarily mounted in the head and carries a disk 36 to which an elliptical gear 37 is fastened. The gear 37 engages with an 55 elliptical gear 38 that is fastened to a disk 39 on arbor 40 which is rotarily supported by the head and a plate 41 fixed to the head. The disk 39 has a crank pin 42 that is designed to engage the slots 43 of a star wheel 60 44. This star wheel is attached to a disk 45 fastened to a shaft 46, which is supported by a partition wall 47 and a plate 48 fixed to the head. The numeral disk 49 is also fastened to the shaft 46. An elliptical gear 50

is attached to the shaft 46 and this gear is 65 engaged with a similar gear 51 that is arranged to, through a crank pin and star wheel, rotate the numeral wheel 52. The same elements are arranged between the wheel 52 and the wheel 53 for driving the 70 latter. The transfer mechanisms of this cylindrical counter are the same as those previously described in connection with the dial counter, and the number of numeral 75 wheels and transfer mechanisms may be added to indefinitely, in order that the counter may indicate the required actions of the machine to which it is to be applied.

As a result of the use of elliptical, eccentric or similar gears and the cranks and star 80 wheels in these transfer trains the last or tenth movement of each lower numeral wheel is transmitted to the next upper wheel very rapidly and very smoothly, without the employment of intermediate gears for obtaining 85 the quick motion, or ratchet and pawls which act intermittently and with blows, or worms and worm wheels, which complicate the structure. The gears may be elliptical 90 or eccentric, and while the term elliptical is used in the claims as qualifying the gears, it is to be understood that that term is intended to include elliptical, eccentric and similar or mechanically equivalent gears which will 95 transmit a variable movement from a lower to a higher wheel. It is also to be understood that while the term wheels is used in the claims, that term is intended to designate both disks and cylinders.

The invention claimed is:

1. A counter having a casing containing lower and higher rotatable numeral bearing wheels, an elliptical driving gear rotatable with the lower of said wheels, an elliptical 100 driven gear intermeshing with the driving gear, and means rotated by said gears for imparting intermittent rotative movements to the higher of said wheels.

2. A counter having a casing containing lower and higher rotatable numeral bearing wheels, an elliptical driving gear rotatable with the lower of said wheels, an elliptical 105 driven gear intermeshing with the driving gear, and a crank and a star wheel driven by said gears and adapted to rotate the higher 110 of said wheels.

3. A counter having a casing containing lower and higher rotatable numeral bearing wheels, an elliptical driving gear rotatable with the lower of said wheels, an elliptical 120 driven gear intermeshing with the driving gear, a crank pin rotatable with the driven gear, and a star wheel engaged by the crank pin and adapted to rotate the higher 115 of said wheels.

4. A counter having a casing containing 125 rotatable numeral wheels, a pair of variable speed intermeshing gears arranged be-

tween said wheels and intermittently rotated by one of said wheels, and means rotated by said gears and adapted to impart quick intermittent rotative movements to the higher of said wheels.

5. A transfer movement for a counter comprising a driven wheel, an elliptical driving gear, an elliptical driven gear, and means rotated by said gears for imparting inter-

mittent rotative movements to said driven wheel.

6. A transfer movement for a counter comprising a driven wheel, an elliptical driving gear, an elliptical driven gear, a crank rotated with the driven gear, and a star wheel 15 connected with said driven wheel and rotated by the crank.

OWEN L. SEWARD.
